UNITED STATES PATENT OFFICE.

JOHN H. RUCH AND LEWIS A. BAKER, OF ELGIN, ILLINOIS.

PUMP MECHANISM.

SPECIFICATION forming part of Letters Patent No. 722,385, dated March 10, 1903.

Application filed February 6, 1902. Serial No. 92,767. (No model.)

To all whom it may concern:

Be it known that we, JOHN H. RUCH and LEWIS A. BAKER, citizens of the United States of America, residing in Elgin, in the county of Kane and State of Illinois, have invented certain new and useful Improvements in Pump Mechanism, of which the following, taken in connection with the accompanying drawings, is a specification.

10 The first of the objects of this invention is the provision of an improved form of driving mechanism for actuating pumps which are to be driven by power belts or shafting, which said improvement will be simple in construction and therefore cheap to construct, while at the same time efficient and durable in operation.

15 The invention will be best understood by reference to the accompanying drawings, 20 showing the improvement embodied in preferred form, and in which—

Figure 1 is an elevation of a pump embodying our improvements; Fig. 2, a view with parts in section taken on the line 2 of Fig. 3; 25 Fig. 3, a sectional view, on a larger scale, taken on the line 3 of Fig. 1; and Fig. 4, a view of a detail, showing the driving-gear with its cam.

In carrying out our invention we first provide a suitable standard 5, to which is secured a pump 6, which may be of any preferred construction and which has the usual stuffing-box 7 at the upper end, through which projects the plunger 8, which in the 35 construction employed in connection with our improvement is extended upwardly and provided with a guide-slot 9, arranged to engage the shaft 10, as shown, and has secured to it by a pin 11 a roller 12, which is adapted to engage with a cam 13, formed in a gear 14, preferably upon the inside face thereof, so that the plunger extension, which contains the slot 9, may operate between the gear and the standard 5.

40 The gear 14 is arranged to be driven by a pinion 15, carried on a driving-shaft 16, which receives its motion from a suitable belt-pulley 17 or other mechanism of like kind.

The cam is preferably arranged in the form

of a groove, as shown, and constructed to receive the cam-stud, comprised of the pin 11 and roller 12, with a small amount of free movement—that is, just sufficient to permit a rotation of the roller 12 within the cam-groove with a minimum amount of friction. 50

The engagement between the slot 9 and the shaft 10 operates to drive the plunger 8, so that it will have a reciprocating movement in a straight or rectilinear path and without any side strain upon the cam or other portions of the mechanism, the reciprocating movement being imparted to the plunger by means of the rotation of the gear 14 with its cam, as described.

Having thus described our invention, what we claim as new, and desire to secure by Letters Patent, is—

1. In a pump mechanism the combination of a cylinder, a supporting-standard, a plunger operating in the cylinder and having a slotted extension on the plunger-rod, bearing a cam-stud, a shaft in the standard passing through the slot of said plunger extension, and carrying on the outside thereof a gear-wheel provided with an eccentric cam-slot engaging the cam-stud on the plunger-rod to reciprocate the same. 75

2. In a pump mechanism the combination with a pump-cylinder and a supporting-standard, of a plunger-rod having an integral extension in direct line with the cylinder provided with a slot and a cam-stud, an arbor fixed in the standard passing through the slot of the plunger-rod extension and carrying outside of said rod a gear-wheel provided with a cam-slot engaging the cam-stud of the plunger-rod, and means for driving said gear-wheel to reciprocate the plunger-rod, said driving means acting from a rigid support outside the line of thrust of the plunger. 90

In testimony whereof we have hereunto set our hands in the presence of two subscribing witnesses.

JOHN H. RUCH.
LEWIS A. BAKER.
